GARMENT SUPPORTING MEANS FOR WARDROBE TRUNKS

Filed Jan. 18, 1924

Patented Feb. 10, 1925.

1,525,446

UNITED STATES PATENT OFFICE.

WADE H. HARRISON, OF PETERSBURG, VIRGINIA.

GARMENT-SUPPORTING MEANS FOR WARDROBE TRUNKS.

Application filed January 18, 1924. Serial No. 687,050.

To all whom it may concern:

Be it known that I, WADE H. HARRISON, a citizen of the United States, residing at Petersburg, in the county of Dinwiddie and

5 State of Virginia, have invented certain new and useful Improvements in Garment-Supporting Means for Wardrobe Trunks, of which the following is a specification.

This invention relates generally to the art 10 of wardrobe trunks and has more particular reference to the garment supporting means employed in conjunction therewith, the primary object of the invention being to substantially improve and simplify over de- 15 vices of this general character.

An additional object of the present invention resides in the provision of a garment supporting means for wardrobe trunks of either the hinged or rigid end type where- 20 in the same may be removed as a unit from the trunk and associated with means positioned within a closet or the like, whereby the garments may be conveniently supported therein after the traveler has reached his 25 destination.

A still further object of the invention is to provide means of the above character wherein the garment hanger supporting elements per se may be extended outwardly from the 30 trunk after the same has been opened for thereby permitting ready access to be made to different articles of apparel that are necessarily closely related when the trunk is in its closed position.

35 Yet another object of the invention resides in the provision of a garment supporting means for wardrobe trunks wherein the garment hanger supports per se may be so manipulated as to allow the easy positioning 40 of the garment hangers thereon.

With the above and other objects in view as the nature of the invention will be better understood, the same comprises the novel form, combination and arrangement of parts 45 hereinafter more fully described, shown in the accompanying drawing and claimed.

In the drawing wherein like reference characters indicate corresponding parts throughout the different views,—

50 Figure 1 is a fragmentary vertical transverse sectional view through a conventional type wardrobe trunk equipped with my improved garment hanger supporting mechanism.

55 Figure 2 is also a fragmentary vertical sectional view, taken upon the line 2—2 of

Figure 1 and looking in the direction of the arrows for disclosing in front elevation, my improved clothes hanger supporting mechanism.

60 Figure 3 is a detail vertical sectional view through one of the bracket members a pair of which are secured in spaced relation to one of the walls of the inner side of the door of a closet whereby certain of the elements of the present garment hanger supporting mechanism may be entirely removed from the wardrobe trunk and placed within the closet after the traveler has reached his 65 destination, and

70 Figure 4 is a front elevational view of one of the walls on the inner side of a closet door showing said pair of brackets secured thereto.

75 First having reference to Figures 1 and 2, wherein there is disclosed the application of my improved garment supporting mechanism for wardrobe trunks, the type of trunk employed in this instance includes a relatively large casing 5 open at its upper 80 end and equipped at this end with a well known form of hinged lid 6 it being also well known that the front wall of this casing is hinged at 7 to one of the side walls thereof whereby the same may be readily opened for 85 allowing the clothes to be removed from or positioned within the trunk.

90 My invention per se embodies the provision of a sheet metal strap 8 that is secured through the medium of rivets or the like, to the interior of the casing 5 and specifically the rear wall thereof and this at the upper open end of said casing, said strap being formed at its opposite ends with 95 forwardly extending portions 9 that fit closely against the side walls of the casing and are also secured thereto through the medium of rivets or the like.

100 Adjacent its opposite ends the strap 8 carries a pair of vertically arranged metallic plates 10—10 to which are secured the inner ends of forwardly extending horizontally arranged hollow metallic arms 11 that terminate short of the front wall of the casing 5 of the wardrobe trunk. Each of 105 these hollow arms is formed at its bottom wall with a longitudinal slot of relatively elongated nature 12 Figure 1, which terminates slightly inwardly of the front end of said hollow arms.

110 Freely slideable upon each of the hollow arms 11 is a similarly shaped relatively long

hollow tube 13 that co-operates with the hollow arm 11 for providing a rigid support for a number of the conventional type clothes hangers 14.

5 The front closed end of each of the hollow tubes 13 carries a vertically arranged stop plate 14 for limiting the sliding movement of the clothes hangers in an outward direction upon the support thus provided, while 10 the rear ends of said tubes are formed with vertical lugs 13' for engaging the clothes hangers and drawing the same outwardly of the trunk when the tubes 13 are slid forwardly.

15 Further, each of said hollow tubes 13 carries adjacent its opposite ends pendant brackets 15—15 upon which are supported in vertical positions guide tubes 16—16 within which are slidably arranged latch 20 bolts 17—17, it being noted from a consideration of Figure 1 that the lower side of each of these hollow tubes is provided with openings registering with the upper open ends of said guide tubes 16—16 whereby 25 said latch bolts may be forced therethrough and also through the slots 12 in the hollow arms 11—11 and this through the medium of coiled springs 18—18 for preventing in one instance an initial sliding 30 movement of the hollow tubes with respect to the hollow arms, and in another instance the total disengagement of said hollow tubes with respect to the hollow arms.

35 Each of the latch bolts 17 is provided at its lower end with a laterally extending lug 19 that extends outwardly through a slot in the respective guide tubes 16. These projecting lugs are adapted to be engaged by the front ends of pivoted finger actuated 40 levers 20 and 21.

45 From the foregoing it will at once be apparent that after the lid 6 and front hinged wall of the trunk have been opened, the garments carried by the hangers 14 may be moved outwardly of the trunk by actuating the foremost finger levers 21 which will thereby retract the latch bolt 17 at the front

side of the trunk, after which the hollow tube 13 may be moved outwardly upon the hollow arms 11.

50 Upon one of the walls or the inner side of the door of a closet of a hostelry or other place where the traveler is stopping, there is secured a pair of spaced brackets 22—22, Figure 4, the central portion of each being pressed outwardly for spacing said central portions from the wall or door of the closet and allowing pendant metal fingers 23—23 carried by the inner ends of a hollow tube 13 to be engaged therewith whereby the 55 clothes may be conveniently supported upon said hollow tubes through the medium of the clothes hangers 14.

60 It will thus be seen that I have provided a highly novel and efficient garment hanger supporting mechanism for wardrobe trunks and one that will answer all of the purposes above ascribed as well as meeting with all of the requirements for a successful commercial use.

65 Minor changes may be made in the invention without departing from the spirit and scope of the appended claim.

70 Having thus described my invention, what I claim as new and desire to secure by Letters Patent is:—

75 A hanger support comprising telescopic arm sections, means for supporting the inner arm section and located at one end thereof, said section having at its opposite end a 80 beveled surface, said section being provided between said supporting means and said beveled surface with a longitudinally disposed slot, and a plurality of spaced bolts carried by the outer arm section and engageable in the slot of the inner arm section and adapted to encounter the beveled surface of the inner arm section successively as the outer arm section is moved with relation to the inner arm section.

85 90 In testimony whereof I affix my signature.

WADE H. HARRISON.
